United States Patent Office

Des. 189,204
Patented Nov. 8, 1960

189,204

PITCHER

Margaret F. C. Carty, P.O. Box 178, Plainfield, Vt.

Filed June 17, 1960, Ser. No. 61,005

Term of patent 3½ years

(Cl. D44—21)

Fig. 1

Fig. 2

Fig. 3

Fig. 4

Fig. 5

Fig. 6

Figure 1 is a perspective view of a pitcher, as viewed from one side, showing my new design;

I claim:

The ornamental design for a pitcher, as shown.
